UNITED STATES PATENT OFFICE.

EDWARD B. HESS, OF NEW YORK, N. Y., ASSIGNOR TO ROYAL TYPEWRITER COMPANY, INC., OF NEW YORK, N. Y., A CORPORATION OF NEW YORK.

TYPEWRITING MACHINE.

Application filed May 3, 1924. Serial No. 710,799.

To all whom it may concern:

Be it known that I, EDWARD B. Hess, a citizen of the United States, residing at New York, in the county of New York, 5 State of New York, have invented certain new and useful Improvements in Typewriting Machines, of which the following is a specification.

This invention relates to the paper feeding and guiding mechanism of typewriting machines. In the Royal Standard machine as heretofore marketed, the paper is fed under the platen and held in yielding contact therewith by a group of rolls mounted 10 in frames which can be adjusted to withdraw the rolls from the platen when it is desired to arrange the paper upon the platen. These combined feeding, guiding, and pressure rolls cooperate with pressure 15 rolls which normally hold the paper, after passing around the front of the platen, with a yielding pressure on the upper portion of the platen. Means have heretofore been provided, and as shown in prior patents 20 issued to the Royal Typewriter Company, Inc., for so moving these upper pressure and guiding rolls that they may be changed from their normal or working position on top of the platen to a position above and in 25 rear of the platen and in rear of the paper table.

In the Royal Standard machine, the top pressure rolls are mounted on a horizontally arranged rod extending from one end of the platen to the other and beyond the ends thereof, and this rod is mounted in what is called a bail comprising side arms or members which are pivotally connected with the carriage frame in rear of the platen and a 30 considerable distance therefrom. These side arms of the bail are braced by a rod which extends from one side arm to the other, and springs are employed for holding the rolls on the platen. While normally the bail holds the pressure rolls yieldingly and with equal pressure upon the platen, it sometimes happens that in a careless use of the machine the bail is bent or misshaped so that a pressure roll on one side 35 of the machine bears with greater pressure on the platen than the roll on the opposite side thereof. It is the object of my present invention to remedy this difficulty in such manner that even though the bail be bent or

misshaped when in use, such irregularity 55 may be remedied.

In carrying out my invention I employ a bail as heretofore and preferably the rod which carries the pressure rolls is mounted in bearings which permit the rod to move 60 vertically or radially towards and from the platen and yielding devices, such as coiled springs, are arranged in the bearings and exert pressure on the opposite ends of the rod tending at all times to press the rolls 65 toward the platen. These springs operate automatically. This way of mounting the roll carrying rod in open bearings and employing springs in said bearings is, however, claimed in my application Serial No. 70 710,797, filed May 3, 1924.

In the present application I have shown, described and claimed another way of regulating the pressure of the rolls on the platen. I do this by employing pivot screws 75 for the rear ends of the roll carrying arms which have eccentric portions enabling me to so adjust the pivots on opposite sides of the machine as to cause the arms of the bail to so hold the rod which carries the pressure rolls as to cause said rolls to bear with 80 equal pressure upon the platen.

In the accompanying drawings:—

Figure 1 is a sectional view with parts in elevation showing how my improvements 85 are applied to the bail which carries the upper pressure rolls.

Figure 2 is a plan view of parts of the mechanism shown in Figure 1.

Parts of a typewriting machine carriage 90 frame are indicated at A, and B indicates a platen. C indicates a shift rail. The paper table is indicated at D and E indicates the paper pan or guide beneath the platen. One of the arms of the bail is indicated at G. 95 The two arms, one on each side of the machine, are of substantially the same shape and construction. The arm G is pivoted to the carriage at F and the two arms G are connected with each other as heretofore by a cross piece N which may be the margin stop rail of the machine as heretofore. At its front end each arm G is enlarged as indicated and formed with a vertical or radial slot T and the roll carrying rod M has its 100 ends mounted in these slots which are of such length as to allow the opposite ends of the rod to have slight vertical or radial 105

movement. Each arm G is formed with a laterally projecting lug g' and between this lug and one end of the rod M is interposed a spring S which tends to press the rod M with the rolls towards the platen and hold the rolls with yielding pressure thereon. This feature properly considered is claimed in my application Serial No. 710,797, filed May 3, 1924.

10 The outer ends of the arms G with the pressure rolls R are drawn toward the platen by springs H, each spring being connected at one end as indicated at h to the adjacent arm, the lower end of the spring being connected at h' to the carriage frame. By reference to Figure 2 it will be observed that the pivot screw F is formed with a threaded portion f which engages the cross piece or margin stop rail N and with an eccentric portion f' which fits an opening in the rear portion of the arm G. By turning the screw F, the pivotal axis about which the arm G turns may be changed. In this way should the bail as a whole become twisted or bent out of shape so as to cause the pressure rolls to bear with unequal pressure on the platen, by adjusting the screws F this difficulty may be remedied.

I can rely alone upon the adjustment of the screws F to accomplish the result mentioned, but I prefer to employ this feature of my invention in connection with the

yielding devices at the front end of the bail arms above referred to.

I claim as my invention:

35 1. In a typewriting machine, the combination with the platen of arms pivotally mounted in rear of the platen, pressure rolls carried by the front ends of said arms, and bearing upon the platen, and adjustable 40 means for shifting the pivotal axis about which the rear ends of the arms move.

2. In a typewriting machine, the combination with the platen of upper pressure rolls, a rod on which they are mounted, bail arms 45 by which said rod is carried, and pivot members for the arms having eccentric portions on which the arms are pivoted, said pivot members being adjustable to change the pivotal axis of each arm.

50 3. In a typewriting machine, the combination with the platen of bail arms, pressure rolls bearing upon the platen, a rod on which the rolls are mounted, yielding devices carried by the front ends of the bail arms and bearing upon the roll carrying rod, and means for pivotally connecting the bail arms with the carriage frame comprising pivot members having eccentric portions 55 about which the bail arms move.

60 In testimony whereof, I have hereunto subscribed my name.

EDWARD B. HESS.
